UNITED STATES PATENT OFFICE.

JOHN E. ZMUDZINSKI, OF BROOKLYN, NEW YORK.

ALARM-LOCK.

1,254,559.

Specification of Letters Patent. Patented Jan. 22, 1918.

Application filed April 3, 1915. Serial No. 18,975.

To all whom it may concern:

Be it known that I, JOHN E. ZMUDZINSKI, a subject of the Emperor of Germany, residing at Brooklyn, in the county of Kings 5 and State of New York, have invented certain new and useful Improvements in Alarm-Locks; and I do hereby declare the following to be a full, clear, and exact description of the invention, such as will enable others skilled in the art to which it 10 appertains to make and use the same.

This invention relates to locks, and the primary object of the invention is to associate with a lock embodying a slidable 15 latch, a signaling mechanism which will sound an alarm upon malicious tampering with the lock.

Another object of this invention is to provide an alarm attachment for a lock, 20 which is practically burglar-proof, in that, it will sound an alarm upon the unlocking of the lock.

Another object of this invention is to provide an alarm attachment which embodies a bell, a rotatable sleeve which is connected to the sliding lock latch, a central pin which is rotatably mounted in said sleeve and carries a transversely extending swinging member, and to connect strikers for the 25 bell to said rotatable sleeve for sounding an alarm upon the rotation of the sleeve and the central pin carried thereby.

With the foregoing and other objects in view, this invention consists in certain novel 30 features of construction, combination and arrangement of parts as will be hereinafter more fully described and illustrated in the accompanying drawings and claimed.

In describing the invention in detail, reference will be had to the accompanying 35 drawings, wherein like characters designate like or corresponding parts throughout the several views and in which,

Figure 1 is a central sectional view taken 40 through the improved alarm lock,

Fig. 2 is a plan view of the alarm sounding mechanism,

Fig. 3 is a sectional view through the bell or signal,

Fig. 4 is a fragmentary view of a part 45 of the locking mechanism,

Fig. 5 is a cross sectional view on the line 5—5 of Fig. 1,

Fig. 6 is a sectional view taken through 50 a part of the alarm sounding mechanism,

Fig. 7 is a sectional view through the key used for unlocking the lock, and

Fig. 8 is a cross sectional view on the line 8—8 of Fig. 7.

Referring more particularly to the drawings, 1 designates a fragment of a door or other hinged member which is to be locked in a closed position, and which has a spring controlled locking latch 2 carried thereby, the shank of which projects transversely 60 through the door and has a spiral spring 3 coiled about the same. One end of the spiral spring 3 engages a shoulder 4 formed in the door, by the cutting out of a recess 5 therein, and the other end of the spring 65 abuts the inner end of the latch 2.

The latch 2 has an arm 9 secured thereto, which arm curves outwardly from the latch and is pivotally connected at 10 to a second arm 11. The arm 11 has one end 70 secured to a sleeve 12. The sleeve 12 is rotatably mounted within a second sleeve 13, which is inserted in the door 1 and has formed thereon a key socket 14. The sleeve 12 projects through the sleeve 13 and has 75 communication with the key socket 14, as is clearly shown in Fig. 1 of the drawings. The sleeve 12 extends outwardly of the door 1, upon the side opposite to the key 80 socket 14 and has a transversely extending flange 15 formed thereon, which engages the surface of the door. A sleeve 16 is mounted upon a section of the sleeve 12 which projects out of the door, and has a pair of disks 17 and 18 secured thereto in 85 spaced relation to each other, which have their peripheries cut away, as is shown at 19, forming the peripheral extending lugs 20, to which are secured metallic straps 21. Bell strikers 22 are carried by the metallic 90 straps 21 and they extend beyond the periphery of the disks or outstanding lugs 20 of the disks 17 and 18, and are adapted to strike against spring tongues 23 which are formed upon and spaced circumferentially 95 about the inner surface of an alarm bell 24. The spring tongues 23 are positioned in 100 circumferential rows, one above the other, so as to receive the strikers 22 carried by both of the disks 17 and 18.

The bell 24 is supported by a supporting bracket 25, which has a collar 26 formed thereupon intermediate its ends. The bracket 26 is substantially semi-circular shaped in plan and has its ends bent trans- 110

versely, as is shown at 27, and secured to the base of the lock. A depending sleeve 28 extends inwardly from the central axis of the bell 24 and is secured thereto by any suitable means (not shown), such as a screw, rivet, etc. The sleeve 28 is received in the collar 26 of the bracket 25 and is soldered to the same. The sleeve 28 is provided with internal screw threads, as shown at 29, which are provided for engagement with external screw threads 30 which are formed upon a pin 31. The pin 31 extends upwardly through the sleeve 12, and has its lower end sharpened to form a substantially pyramidal shaped point 32, immediately above the face of which the pin is cut to form a triangular shape in cross section, as indicated at 33. A swinging member 35 is passed through the pin 31 adjacent its upper end, which striking member has its ends bent downwardly and inserted through openings 36 and 37 formed in the disks 17 and 18 upon opposite sides of the central axis of the disks and the sleeve, as is clearly shown in Fig. 1 of the drawings.

The sleeve 12 is provided with internal screw threads 38 formed therein, which are positioned above the lower end of the triangular extension 33 of the pin 31. The screw threads 38 extend only over a short distance of the length of the sleeve and are provided for meshing engagement with the external screw threads 39 which are formed upon a key 40. The key 40 has a barrel 41, which is provided with a longitudinally extending recess 42 extending inwardly from one end of the barrel and terminating in a pyramidal shaped recess 43 for receiving the pyramidal end 32 of the pin. The recess 42 of the key barrel 41 has a triangular shaped portion 44 formed therein, which triangularly shaped portion is provided for engagement with the triangular portion 33 of the pin 31 for rotating the pin upon rotation of the key. The handle 45 is formed upon the key 40 to provide for the manual rotation thereof.

To unlock the improved alarm lock heretofore described the key 40 is inserted in the sleeve 12 and shoved on the pin 31 until the threads 38 and 39 begin to engage and upon turning the key, said key will thread along the inside of the sleeve 12 until the threads 38 and 39 are in entire engagement. During this time the pin 31 has been threading out of engagement with the sleeve 12 and into the sleeve 28 and the bell has been consequently rung through the bar 35 which rotates the disks 17 and 18, which throws the rings 22 outward by centrifugal force

against the bell. When the threads 38 and 39 are in entire engagement, the pin 31 is out of threaded engagement with the sleeve 12 and upon further rotation of the key 40, the sleeve 12 will be turned, and with it the latch 2. Thus, it will be seen that an alarm lock is provided in which the alarm has to be run a predetermined time before the latch can be operated.

From the foregoing description taken in connection with the accompanying drawings the advantages of construction and of the method of operation of the improved alarm lock will be readily apparent to those skilled in the art to which this invention appertains and, while in the foregoing description, the principle of the operation of this invention has been described together with various features of construction, it is to be understood that certain minor features of construction, combination and arrangement of parts may be altered to suit practical conditions provided such alterations are comprehended within the scope of what is claimed.

What is claimed is:—

1. In an alarm lock, a sleeve, a shank rotatably mounted in said sleeve and extending outwardly of the same, a bell inclosing said sleeve and shank, a latch operatively connected to said sleeve, a second sleeve rotatably inclosing said first mentioned sleeve, a series of disks carried by said second sleeve, means carried by said disks for striking said bell when the disks are rotated, and means for engaging said first-mentioned sleeve and shank to operate said latch and ring said bell.

2. In an alarm lock, a sleeve, a shank rotatably mounted in said sleeve and extending outwardly of the same, a bell inclosing said sleeve and shank, a latch operatively connected with said sleeve, a second sleeve rotatably inclosing said first named sleeve, a series of disks carried by said second sleeve, means carried by said disks for striking said bell when the disks are rotated, the inner portion of said shank being reduced and non-circular in cross section, and a key for rotating said first-mentioned sleeve to operate said latch, said key having an aperture non-circular in cross section to receive the reduced end of said shank, whereby said shank is rotated and the bell rung.

In testimony whereof I affix my signature in presence of two witnesses.

JOHN E. ZMUDZINSKI.
